ONE-PIECE BUCKLE

John A. Devendor and William A. Devendor,
Jackson Heights, N. Y.

Application April 28, 1934, Serial No. 722,858

6 Claims. (Cl. 24—198)

This invention relates to adjustable straps for garments and more particularly to slide and loop elements employed in said straps for securing the ready assembly and adjustment thereof.

5 In prior slide constructions with which we are familiar, provision has been made of a slide of generally rectangular outline having a single central crossbar. Where such a slide is used a strap end is first threaded successively through the 10 openings or slots of the slide and is then required to be threaded a second time through both of said openings. This is an awkward and time-consuming operation, since the slide openings confine the ribbon quite closely. The second set 15 of threading operations is particularly difficult because each opening is already occupied by one stretch of the strap and also because the leading end of the strap is apt to become bunched or frayed as it is passed through one opening after 20 another. It is necessary, moreover, to stitch the strap to prevent dislodgment of the first formed loop because the second loop has extensive rubbing engagement with the first loop, and will pull the first loop out when the slide is adjusted unless 25 the first loop is positively retained in place by stitching.

It is an object of the present invention to avoid the necessity for stitching the first loop in place. To this end, provision is made of a slide 30 having four successive, distinct slots, the two inner slots being separated by a central tongue or crossbar about which the inner strap loop is passed, and the two outer slots being separated from the inner slots and adapted to receive the strap when it is looped through the second time. The inner slots are narrow and are adapted to bend the strap sharply and to bind it quite snugly so that no stitching is necessary. A further factor tending to obviate the stitching is the fact 40 that the first and second strap loops do not pass through the same slots and do not, therefore, have substantial frictional engagement with one another.

A further object of the invention is to provide 45 a novel slide construction which obviates the necessity for threading the strap ends through the slots or openings in the slide and which, instead, enables the strap to be slid into each slot edgewise through a narrow passage extending into the slot through the periphery of the slide. As applied to the inner slots of the slide embodying this invention, this feature has the further 50 advantage that the inner slots may be made narrower than heretofore, since the strap can be

inserted edgewise into a slot through which it could not be threaded.

In accordance with a further feature of the invention the provision of slots for facilitating the insertion of the ribbon is applied also to the 5 loop which forms part of the shoulder strap.

Other objects and advantages will hereinafter appear.

In the drawing forming part of this specification, and illustrating certain preferred embodiments thereof,

Figure 1 is a fragmentary front elevation illustrating a portion of an undergarment having a shoulder strap embodying features of the invention applied thereto; 15

Figure 2 is a fragmentary view in elevation and on a larger scale than Figure 1 illustrating more in detail the slide and loop construction of Figure 1;

Figure 3 is a longitudinal, sectional view of the 20 structure of Figure 2, the section being taken on the line 3—3 of Fig. 2 looking in the direction of the arrows;

Figure 4 is a perspective view of the slide disclosed in the preceding figures; 25

Figure 5 is a perspective view of another form of slide embodying features of the invention;

Figure 6 is a perspective view of the loop disclosed in Figures 1 to 3; and

Figure 7 is a perspective view of another form 30 of loop embodying features of the invention.

In the embodiments of Figures 1 to 4 and 6 disclosure is made of an undergarment 1 having a strap length or ribbon 2 secured thereto. The ribbon is passed through the lower opening 3 of a loop 4 and doubled back on itself, both ends of the ribbon being stitched to the undergarment. A second strap length or ribbon 5 is passed through an upper opening 6 of the loop 4. One end of this ribbon is passed successively through 40 slots 7 and 8 of a slide 9, the ribbon end passing around a central cross-bar 10, which, as shown, may be provided with teeth 11, if desired, to increase the grip of the cross-bar upon the ribbon. The ribbon extends downward from the cross-bar 45 through the slot 6 of the loop 4 and thence upward through slots 12 and 13 of the slide. The ribbon extends thence over the shoulder of the wearer down to the back of the garment. The end of the ribbon which is not seen in the drawing is 50 stitched to the back of the garment.

When it is desired to shorten or lengthen the shoulder strap the slide 9 is seized and slid up or down the outer stretch of the ribbon 5. It will be observed that the inner ribbon loop which 55

embraces the cross-bar 10 has very slight contact with the outer ribbon loop 14, and hence there is little tendency for the inner loop to be dislodged when the length of the shoulder strap 5 is adjusted.

The chief item of expense which has been involved in prior adjustable shoulder straps has been the cost of assembling the slide and loop with the ribbon. One reason why this operation 10 has been expensive has been that the ribbon had to be threaded repeatedly through the same openings of the slide. With both the slide and loop, moreover, the ribbon had to be threaded through 15 endwise just as a needle is threaded and this operation could not be performed rapidly, particularly if the ribbon ends were at all frayed or bunched.

In accordance with the present invention, each 20 of the slots 12 and 13 can be entered from the periphery of the slide through an obliquely extending narrow passage 15 having a flared mouth. The passage 15 inclines inward from the end of the slot to facilitate the smooth and continuous 25 passage of the ribbon in through the passage 15 and across to the end of the slot remote from the passage. The obliqueness of the slot further causes the end of the passage which communicates with the slot to be disposed between the ends of the slot so that an overhanging shoulder 30 16 is formed behind which the trailing edge of the inserted ribbon may be located and by which it may be retained.

Each of the slots 7 and 8 communicates at one 35 end thereof with the periphery of the slide through a passage 17. The passage 17 is located out of alignment with the slot and an oblique portion 18 is provided for guiding the ribbon into the slot. A shoulder 19 on the slide extends across the end of the slot to retain the inserted 40 ribbon. With this construction, the assembly of the ribbon and the slide can be expeditiously and economically effected. The ribbon end is first passed edgewise into the slot 8, then edgewise into the slot 7, or vice versa. Another portion of the 45 ribbon is then passed edgewise into the slot 12 and then into the slot 13. This completes the assembly of the ribbon with the slide.

The sides of the slide which extend across the closed ends of the slots 7 and 8 are desirably provided with pressed reinforcing ribs 7a to stiffen 50 the slide in its weakest and most flexible portions.

The intermediate portion of the ribbon may be assembled with the loop 4 in a similar manner. Each of the slots 3 and 6 of the loop 4 is provided with an obliquely extending passage 20 enabling the ribbon to be slid edgewise into the slot from the periphery of the loop. The ribbon may, if desired, be fully assembled with the slide and thereafter assembled with the loop since it is not necessary to have a free end of the ribbon for 55 threading through the loop. The other length of ribbon 2 is inserted edgewise into the unoccupied slot of the loop 4. This operation may also be effected after the ends of the ribbon 2 have been 60 stitched to the garment.

With the construction described, it is unnecessary to stitch the end of the ribbon which is applied to the slide because this ribbon end is subjected to no great force tending to dislodge it. 65 The slots 7 and 8, moreover, may be made considerably narrower than the slots of previous slides, not only because each slot is intended to receive but a single length of ribbon but also because a ribbon can be passed edgewise into a slot so narrow that threading through of the ribbon would 70

be impossible. The narrower the slots 7 and 8 are, the sharper are the turns formed in the ribbon portion which passes through them, and the more effective is the snubbing action produced by the walls of the slots.

The slide illustrated in Figure 5 is like the slide of Figures 1 to 4 with the exception that the slots 12a and 13a are entered through their ends rather than through their sides. In this construction each slot communicates with the periphery of the 10 slide through a passage 21. A shoulder 22 extends completely across the normal width of the slot and an oblique passage portion 23 is provided for guiding the ribbon into the slot.

It is desirable in this form of construction to 15 safeguard the ribbon against possible escape from the slots 12a and 13a through the passages 21 when adjustment is being made. To this end each of said slots is made a little wider at the 20 end remote from the entrance passage than at the end adjacent such passage, the inner wall of each slot diverging slightly from the outer wall thereof as it recedes from the entrance passage. Thus each inner slot wall is inclined slightly and has a slight tendency to shift the ribbon away 25 from the entrance passage when the ribbon is drawn through the slot in either direction.

The loop of Figure 7 differs from the loop of Figure 6 in the same manner that the slide of Figure 5 differs from the slide of Figure 4. Each 30 slot 3a and 6a is entered from its end through a passage 24. A shoulder 25 extends completely across the normal width of the slot and an oblique passage portion 26 serves to permit the ribbon 5 to enter the slot.

While the forms of slides and loops illustrated herein have been described and shown as incorporated in shoulder straps for garments, it will be appreciated that their utility is not confined to such use. These elements may find utility in 40 belts, garters, suspenders, and other articles of wearing apparel. The loops illustrated have utility as slides and reference in the appended claims to slides is intended broadly to apply to any of the structures of Figures 4 to 7 unless inconsistent 45 with the context.

While we have illustrated and described in detail certain preferred forms of our invention, it is to be understood that changes may be made therein and the invention embodied in other 50 structures. We do not, therefore, desire to limit ourselves to the specific constructions illustrated, but intend to cover our invention broadly in whatever form its principle may be utilized.

We claim:

1. A slide for adjustable straps having two distinct pairs of slots therein, all of the slots being disposed in substantially parallel relation, the slide being provided with offset openings in its periphery which communicate with the two inner slots, and being formed with shoulders standing across the entrance ends of said slots.

2. A slide for adjustable straps having two distinct pairs of slots therein, all of the slots being disposed in substantially parallel relation, the slide being provided with offset openings in its periphery which communicate with the two inner slots, and being formed with shoulders standing across the entrance ends of said slots, the slots of one pair being separated from one another by 60 a rough-edged crossbar.

3. A slide for adjustable straps having inner and outer pairs of parallel slots therein and having passages letting obliquely into the slots of the outer pairs through the ends of the slide and 75

passages letting obliquely into the slots of the inner pair through the sides of the slide.

4. A slide for adjustable straps having inner and outer pairs of parallel slots therein and having passages letting obliquely into alternate slots through one side of the slide and passages letting obliquely into the other alternate slots through the opposite side of the slide, each passage entering its slot through a side of the latter.
- 10 5. A slide for adjustable straps having a pair of parallel transversely extending slots therein, one of said slots communicating with the periphery of the slide through a side of the slot near one end thereof, and the other communicating with the periphery of the slide through a side of the slot near the opposite end thereof, said
- 15

slots being of tapering width, each increasing gradually in width toward the end remote from the point of communication with the periphery of the slide.

6. A slide for adjustable straps having inner and outer pairs of parallel transversely extending slots therein, one of the slots of the inner pair communicating with the periphery of the slide through one side of the slide and the other communicating with the periphery of the slide 5 through the other side of the slide, said slide having stiffening ribs disposed across the closed ends of said inner slots.
